TRANSFERRER

William Edward Lundgren, Hopedale, Mass., assignor to Draper Corporation, Hopedale, Mass., a corporation of Maine

Application July 19, 1939, Serial No. 285,252

3 Claims. (Cl. 139—244)

The present invention pertains to bobbin changing mechanism for automatic bobbin changing looms and more particularly relates to the construction of the bobbin transmitters of 5 such mechanisms.

The usual bobbin changing mechanism for looms includes a hopper for holding a reserve supply of bobbins and a transquirer member for transferring the reserve bobbins to the loom 10 shuttle as required. The transquirer commonly 15 comprises a pivoted member having a head which includes a striking surface for engaging the butt of the bobbin during transfer and a supplemental bobbin-engaging member commonly in 20 the form of a tip-engaging fork. The said striking surface of the transquirer engages hardened steel rings on the bobbin butt and eventually becomes worn to the extent that the transquirer will not operate properly. In the usual prior construction, the transquirer has the head and striking face formed integrally with the rearwardly 25 extending arm of the main body member of the transquirer, so that when such face becomes worn the entire body member must be discarded.

A principal object of the present invention is to provide a transquirer comprising a body portion, a detachable piece having formed thereon the aforesaid striking surface for engaging the butt of the bobbin, a supplemental bobbin-engaging member as aforesaid, and means carried by such supplemental member for detachably clamping the detachable piece to the body portion of the transquirer.

The foregoing and other objects of the invention are accomplished in the construction illustrated on the accompanying drawing, of which:

Fig. 1 is a fragmentary view, partly in section and partly in elevation, of bobbin changing mechanism having the preferred embodiment of 40 my improved transquirer applied thereto;

Fig. 2 is a view in perspective of one end of the body portion of said transquirer;

Fig. 3 is a view in perspective of the detachable piece of the transquirer; and

Fig. 4 is plan view, partly in section, of the rearward end of the transquirer.

The bobbin changing mechanism shown on the drawing, except for the improved transquirer, is of conventional construction and is accordingly 50 but fragmentarily illustrated. Such mechanism includes a hopper for holding reserve bobbins, of which hopper the drawing shows a disc 1 rotatably mounted on a stud 2 and having pockets 3 for receiving the butts of reserve bobbins 4, the 55 tips of the bobbins being supported by another

disc, not shown. The hopper is rotated, to successively present the bobbins 4 in transferring position adjacent a guide 5, by a suitable pawl 6 engaging a ratchet wheel 7. The hopper carries the usual fixed stud 8 on which the transquirer to be described is pivoted.

The transquirer shown includes a relatively large main or body portion consisting of a depending arm 9 and a rearwardly extending arm 10 integrally joined with a hub portion 11 which 15 engages the stud 8. The rearward or free end of the arm 10 is located over the bobbin 4 in transferring position and is provided with a head 12. In the present construction, the head 12 consists simply of the end portion of the arm 10 20 and a laterally extending flange as shown. The transquirer further includes a detachable piece 13 for engaging the butt of the bobbin during transfer and a suitable supplemental bobbin-engaging member such as the fork member 14.

The rearward or head end of the arm 10 has a substantially flat, horizontal lower face 15 and a vertical side face 16. The striking piece 13 has an upper surface 17 which fits against the face 15 and also has on its lower side a striking surface 18 for engaging the butt of a bobbin during transfer. The surface 17 is substantially flat, while the striking surface 18 is curved the same as similar surfaces heretofore formed directly on the body portion of the transquirer. The piece 14 must be firmly but detachably secured to the arm 10 and the securing means must be confined within the limited space available. To this end, I prefer to utilize attaching means carried by the supplemental member 14.

In the particular embodiment shown, the arm 10 has a boss 19 which projects laterally from the vertical face 16 and the member 14 is threaded into threads in a bore in this boss. The member 14 is thereby fixed in the arm 10 and 40 extends laterally thereof as usual. The striking piece 13 has an upwardly extending portion provided with a surface 20 which engages the face 16 of the arm 10. A nut 21 threaded onto the member 14 is utilized to clamp the striking piece 45 against the surface 16. To this end, the said upwardly extending portion of the striking piece is provided with an aperture 22 which fits over the boss 19 and a flange 23 around the aperture extends far enough beyond the boss to be 50 engaged by the nut 21.

The angularly related surfaces 17 and 20 on the striking piece 13 fit the similarly related surfaces 15 and 16 on the arm 10, so that the striking piece is held against any possibility of move- 55

- ment. The boss 19, engaging in the aperture 22, further holds the striking piece and accurately positions the latter. Accordingly, no further clamping means than the nut 21 are required.
- 5 The striking piece is quickly and easily detached by merely loosening the nut 21 and unscrewing the member 14, wherefore the striking piece may be replaced when worn. Furthermore, the complete transerrer is no larger than prior one piece 10 transerrers, whereby it may enter down into the shuttle (not shown) during transfer, and will not interfere with other parts of existing looms.

Having fully disclosed the preferred embodiment of my invention, I claim:

- 15 1. A transerrer comprising in combination, a body portion having a hub and a rearwardly extending arm, the rearward end of said arm having a horizontal lower face and a vertical side face, a detachable piece having an upper surface 20 engaging said lower face on said transerrer and further having at its lower side a striking surface for engaging the butt of a bobbin during transfer, said piece extending upwardly in engagement with said vertical side face, a bobbin-engaging 25 fork member fixed in said arm and extending through said upwardly extending portion of said detachable piece, and means on said member for fixing said detachable piece to said arm.

2. A transerrer comprising in combination, a 30 body portion having a hub and a rearwardly ex-

tending arm, the rearward end of said arm having a horizontal lower face and a vertical side face, a detachable piece having angularly related surfaces respectively engaging said horizontal and vertical faces of said arm, said detachable piece having at its lower side a striking surface for engaging the butt of a bobbin during transfer, said arm having a boss projecting laterally from its said vertical face and extending through an aperture in said detachable piece, and means 10 detachably clamping said piece against said vertical face.

3. A transerrer comprising in combination, a body portion having a hub and a rearwardly extending arm, the rearward end of said arm having a horizontal lower face and a vertical side face, a detachable striking piece having angularly related surfaces respectively engaging said horizontal and vertical faces of said arm, said striking piece having at its lower side a striking 20 surface for engaging the butt of a bobbin during transfer, said arm having a boss projecting laterally from said vertical face and engaging in an aperture in said striking piece, a bobbin-engaging fork member fixed in said arm and extending through said boss, and a nut on said member, said nut engaging said striking piece and detachably clamping the latter against said vertical face of said arm.

WILLIAM E. LUNDGREN. 30
